UNITED STATES PATENT OFFICE.

THOMAS J. COSTER, OF DEPEW, NEW YORK.

MACHINE FOR MAKING BATTERY-GRIDS.

SPECIFICATION forming part of Letters Patent No. 737,081, dated August 25, 1903.

Application filed September 2, 1902. Serial No. 121,708. (No model.)

To all whom it may concern:

Be it known that I, THOMAS J. COSTER, a citizen of the United States of America, residing at Depew, in the county of Erie and State of New York, have invented certain new and useful Improvements in Machines for Making Battery-Grids, of which the following is a specification, reference being had therein to the accompanying drawings.

This invention relates to machines for making secondary-battery plates or grids which are formed by spinning the surfaces of the blank plates to form therein concentric grooves the metal from which is spun up, forming concentric rings raised above the surface of the plate to receive and hold the active material of the battery; and its object is to provide a cheap, durable, and efficient machine for the purpose adapted to prepare any size of plate with despatch and accuracy and which is provided with spinning-tools so constructed that the knives may be easily removed and replaced when worn or broken.

To this end the invention consists in providing one or more rows of opposing spindles movable to and from each other and in providing means for holding the plates consisting of a frame longitudinally movable in a plane at right angles to said spindles and between their opposing ends to present the whole surface of the plate to the action of the tools, which are secured in the ends of said spindles and which consist each of a cap into which are set rings spaced apart by spacing-rings, means for rotating and moving the spindles and for moving the plate being also provided; and the invention further consists in providing certain other new and useful features and in the particular arrangement and construction of parts, all as hereinafter more fully described, reference being had to the accompanying drawings, in which—

Figure 1 is a view of a device embodying my invention, showing the spindles in side elevation with portions of the frame and parts in section to show the construction. Fig. 2 is a similar view taken at right angles to that of Fig. 1 and showing the plate and plate-holder in side elevation. Fig. 3 is an elevation showing an end view of the plate-holder and supporting-frame. Fig. 4 is a side elevation of the spinning-tool; Fig. 5, a vertical

central section of the same; Fig. 6, an end view showing the concentric ring-knives, and Fig. 7 a section on the line 7-7 of Fig. 1.

A is the machine-frame, consisting of two I-beams A' and A'', which intersect each other at right angles to form the bed, to which the legs B are attached and from the outer ends of which the posts C and D extend vertically upward, the upper ends of said posts being connected by the cross-bars E, which extend parallel with the I-beams.

Formed on the upper side of the beam A and on the under side of the opposite cross-bar E are V-shaped ribs F, which engage grooves in the ends of the movable spindle carrying posts G and guide said posts as they are moved toward and from each other by the screw-shafts H and H', which shafts engage screw-threaded openings near the upper and lower ends of said posts and are journaled at their middle in bosses I and at their ends in the posts C. One end of the screw-shaft H is provided with a hand-wheel and its opposite end with a bevel-gear, a similar bevel-gear being provided on the end of the screw-shaft H', and journaled in brackets on the post C is a vertical shaft J, provided at its end with bevel-gears to mesh with those on the screw-shafts, so that when the screw-shaft H is turned the shaft H' will be actuated thereby and the posts G moved toward or from each other, the thread on one end of each shaft being a left-hand thread and the thread on the other end of the same shaft being a right-hand thread.

Journaled in bearings G' in each of the posts G is a vertical row or series of spindle-heads K, provided with the squared sockets K' to receive the squared shanks of the tools N and the squared sockets K'' to receive the squared ends of the spindles L, which spindles are journaled in bearings in the posts C and are geared together by the gears M, one of said spindles in each row being extended outward through its bearing and provided with a drive-pulley M'. A plate-carrying frame O, provided with an opening to receive the lead plate to be spun, extends at right angles to the axis of the spindles and in a vertical position across between the adjacent ends of the two rows and is provided with guide-ribs O' on its upper and lower

sides to engage ways in the posts D and lugs I, said posts being slotted at D' to allow said frame O to pass therethrough. The plate holder or frame O is moved longitudinally by 5 a screw-shaft P, journaled at its ends in bearings in the posts D and engaging a screw-threaded opening in the lug R on the lower side of the plate-frame, a hand-wheel being provided on one end to turn said screw-shaft.

10 The spinning-tool N consists of a shank portion N', squared at one end to fit the socket K' in the spindle-head K and provided at the other end with a hollow head or cup N², into which cup are set the tubular ring-shaped 15 knives N³, formed with a cutting lower end and which are spaced apart by the spacing-rings N⁴, a transverse pin N⁵ being provided to hold the knives in place. The spindles of the row at one side of the plate are driven in 20 a direction opposite to that of the spindles of the row at the opposite side of said plate, and each tool of one row is directly opposite and in line with the opposing tool of the other row, so that when the tools are moved into 25 contact with the plate the tools have no tendency to tear, twist, or bend the plate, as the force of one counteracts the force of the other, and as said tools are moved equally toward each other the plate will not be bent 30 laterally, but will be grooved to an equal depth on each side. The tools N are rotated quite rapidly, so that when they are forced gradually into contact with the plate the metal will be spun up into the spaces between 35 the knives and no metal be cut from the plate, and by forming the tool of concentric tubular knives set into the cup and held in place therein in any suitable manner new or different-sized knives may be put in at any time 40 with but little trouble or expense.

Having thus fully described my invention, what I claim is—

1. In a machine for making battery-plates, vertical rows of rotatable spinning-tools journaled in bearings on opposite sides of the machine in axial line with each other, means for driving the opposing tools in opposite directions, separate means for moving said tools from and toward each other, and a plate-holder interposed between the adjacent ends of said tools and longitudinally movable in a plane at right angles to the axes of said tools.
2. In a machine for making battery-plates 55 the combination with the frame, of a plate-holder longitudinally movable in guides on the frame, posts movable in guides on the frame in a direction at right angles to the movement of the holder on opposite sides of the holder, a vertical series of spindle-heads formed with sockets at their opposite ends journaled in bearings in said posts, spinning-

tools fitting in the sockets in the adjacent ends of said heads, spindles journaled in the frame having a sliding engagement with the 65 sockets in the opposite ends of said heads, gears fixed on said spindles and means for moving said posts from and toward each other.

3. In a machine for making battery-plates 70 the combination with the frame, of a plate-holder longitudinally movable in the frame, vertical posts mounted in guides on opposite sides of the frame, spindle-heads journaled in said posts, spinning-tools carried by the 75 adjacent ends of said heads, rotatable spindles having a sliding engagement with the opposite ends of said heads journaled in the frame and means for simultaneously moving said posts from and toward each other, comprising transverse shafts journaled in the frame and each provided with a right and a left hand screw-thread to engage screw-threaded openings in the ends of said posts on opposite sides of said holder, a bevel-gear on 80 one end of each of said screw-shafts, a vertical shaft having bevel-gears on its ends to engage the gears on the screw-shafts, and means for actuating said screw-shafts.

4. In a machine for making battery-plates, 85 the combination with the frame, of a vertical plate-holder mounted in guides transversely of the frame, vertical posts mounted in guides on opposite sides of the holder and movable from and toward the holder, a vertical row of 90 spindles carried by each of said posts, spinning-tools carried by the adjacent ends of said heads, spindles having a sliding engagement with said heads journaled in the frame and means for moving said holder at 95 substantially right angles to the axes of said tools comprising a shaft journaled on the frame and having a screw-thread to engage a screw-threaded opening in the holder.

5. In a machine for spinning battery-grids, 105 a tool provided with an alternating series of concentric knives and spacing-rings, and means for detachably securing said knives and rings in place.

6. In a machine for spinning battery-grids, 110 a tool formed with a shank portion having a squared end and an enlarged hollow head, a series of concentric ring-shaped knives, a series of spacing-rings interposed between said knives, and a transverse pin passing through 115 apertures in said knives, rings and head to secure said knives and rings within the head.

In testimony whereof I affix my signature in presence of two witnesses.

THOMAS J. COSTER.
